[57] **CLAIM**

The ornamental design for a floor lamp, as shown and described.

DESCRIPTION

FIG. 1 is a perspective view of a floor lamp showing our new design;

FIG. 2 is a side elevational view thereof;

FIG. 3 is a top plan view thereof;

FIG. 4 is an enlarged, fragmentary side elevational view of the finial of the lamp shown within circle 4 of FIG. 2;

FIG. 5 is an enlarged, fragmentary side elevational view of the section of the standard shown within circle 5 in FIG. 2;

FIG. 6 is an enlarged, fragmentary side elevational view of the section of the standard shown within circle 6 in FIG. 2;

FIG. 7 is an enlarged, fragmentary side elevational view of the base of the standard shown within circle 7 in FIG. 2;

FIG. 8 is a perspective view of a second embodiment of our new design, the second embodiment differing from the first only by the curving walls of its shade and by the smooth surface of its standard;

FIG. 9 is a perspective view of a third embodiment of our new design, the third embodiment differing from the second only in its shade;

FIG. 10 is an enlarged cross-sectional view thereof as taken along line 10—10 of FIG. 2; and,

FIG. 11 is an enlarged cross-sectional view as taken along lines 11—11 of FIG. 8.
